FIG. 1

FIG. 2

FIGURE 1 is a perspective view of the toy spinning top showing my new design;

FIGURE 2 is a perspective view showing another embodiment of my new design wherein a multi-faceted tapered post is employed therein.

The essential features of my design reside in the portions shown in full lines and are characterized by the particular shaped monorail and support situated above the railway in combination with the toy spinning top, all as shown.

I claim:

The ornamental design for a toy spinning top, as shown and described.
